G. H. BAKER,
CURTAIN STRETCHER,
APPLICATION FILED APR. 26, 1916.

1,235,414.

Patented July 31, 1917.

George L. Baker Inventor
By J. C. Hall Attorney

UNITED STATES PATENT OFFICE.

GEORGE H. BAKER, OF FRUITLAND, MISSOURI.

CURTAIN-STRETCHER.

1,235,414.

Specification of Letters Patent. Patented July 31, 1917.

Application filed April 26, 1916. Serial No. 93,694.

To all whom it may concern:

Be it known that GEORGE H. BAKER, a citizen of the United States, residing at Fruitland, in the county of Cape Girardeau 5 and State of Missouri, has invented certain new and useful Improvements in Curtain-Stretchers, of which the following is a specification.

The present invention relates to certain 10 new and useful improvements in curtain stretchers and has for its primary object to provide a collapsible stretching frame which may easily and quickly be set up for holding a curtain, and readily knocked 15 down for storage.

Further, the invention resides in an improved corner clamp or fastening for uniting the side and end frame members.

Other ends will be set forth as the description progresses and those features of construction, arrangements and combinations of parts on which protection is desired will be claimed in a succinct manner.

In the drawings, wherein is depicted the 25 preferred embodiment of the invention, and wherein like characters of reference designate like parts throughout,

Figure 1 is an elevation of the improved frame;

30 Fig. 2 is a section on line 2—2 of Fig. 1 showing the invention;

Fig. 3 is a side elevation of the corner fastener;

Fig. 4 shows the blank which the fastener embodies;

Fig. 5 is a detailed elevation of the cam; and Fig. 6 is a perspective view of a fastener used in securing a curtain to the frame.

40 Each corner fastening for connecting the frame bars, comprises the body plate 1, of rectangular design, having flanges or wings 2 projecting outwardly from the edges of the body. These wings are bent at right

45 angles to the body and in oppositely projecting pairs to form a channel on each side of the body, the channel on the top side being at right angles to that on the bottom side, and the wings 2 constituting 50 side walls for said channels.

Hinged to the upper edge 3 of one wall of each channel is a keeper bar or plate 4 which is adapted to span the channel and rest on the other wall thereof. To the free 55 end of keeper 4 is hinged a hasp 5 which is provided with a perforation for engaging

over a pin 6 extending outwardly from the side face of the last channel wall.

In practice, the right angularly related ends of the frame bars 7 and 8 are seated 60 in the channels against body 1 and the keeper plates then swung across to permit of the hasps being engaged with the pins 6, thereby locking the frame bars against dislodgment.

As a further means for securing the frame bars in their respective channels, cam locks 9 are provided, these being pivotally mounted between ears 10 struck out from, or otherwise formed on, one of the wings of each 70

pair. The biting or active face of each cam lock is formed with two sets of serrations 11 which are reversely related so that the respective set of the serrations may be used for effectively gripping the frame bar regard-

less at which end of the latter the corner fastening is disposed. These cam locks operate through slots or openings 12 formed in the wings between the supporting ears 10, and are especially adapted for positively 80

holding both large and small frame bars. Suitable means may be employed for securing a curtain to the stretcher frame, although I have shown a preferred fastener in Fig. 6 which comprises resilient jaws 20 85

and 21 joined by a spring coil 22, the upper jaw 20 terminating in a hook 23 over which the curtain may be engaged. A series of

these fasteners are clasped over the outer edges of the frame bars, as shown in Fig. 1, 90 the springy nature of the jaws 20 and 21 affording sufficient friction to hold the fasteners in position.

Thus, it is obvious that the present corner fastener may be cheaply constructed from 95 sheet metal, that the device embodies simplicity and durability, and that the frame bars may easily and quickly be secured in the fastener.

What is claimed is:

1. In a device of the character described, a sheet metal body having wings bent at right angles from the edges in oppositely projecting pairs to form a channel on each side of the body, said channels being disposed at right angles to each other and adapted for receiving frame bars, a keeper plate hinged to one of the wings defining each channel and adapted for spanning the latter and receiving support from the edge 110 of the wing, a pin fixed on the side face of the latter, and a perforated hasp hinged to

- the free end of the keeper and engaging over the pin.
2. In a device of the character described, a sheet metal body having wings bent at right angles from the edges in oppositely projecting pairs to form a channel on each side of the body, said channels being disposed at right angles to each other and adapted for receiving frame bars, a keeper plate hinged to one of the wings defining each channel and adapted for spanning the latter and receiving support from the edge of the wing, and means for securing the free end of the keeper to the last wing.
3. In a device of the character described, a sheet metal body having wings bent at right angles from the edges in oppositely projecting pairs to form a channel on each side of the body, said channels being disposed at right angles to each other and adapted for receiving frame bars, one of the wings defining each channel being formed with an opening, a pair of ears arranged on the wing on opposite sides of the opening, and a cam pivoted between each pair of ears and operating through the wing opening, a keeper pivoted to each perforated wing for swinging over the channel, and means for securing the free ends of the keepers to the other wings of those defining the channels.
4. In a device of the character described, a sheet metal body having wings bent at right angles from the edges in oppositely

projecting pairs to form a channel on each side of the body, said channels being disposed at right angles to each other and adapted for receiving frame bars, one of the wings defining each channel being formed with an opening, a pair of ears arranged on the wing on opposite sides of the opening, a cam pivoted between each pair of ears and operating through the wing opening, a keeper pivoted to each perforated wing for swinging over the channel, and means for securing the free ends of the keepers to the other wings of those defining the channels.

5. In a curtain stretcher, a frame consisting of frame bars and corner fasteners for securing the same together, each fastener comprising a body having a channel on each side arranged transversely one to the other for receiving the bars, and a keeper for each channel hinged to one wall thereof, and means on the other wall of each channel with which the respective keeper is adapted to engage.

In testimony whereof I have affixed my signature in the presence of two witnesses.

GEORGE H. BAKER.
